CLAIM

The ornamental design for a microfiche reader printer,
substantially as shown and described.

DESCRIPTION

FIG. 1 is a front perspective view of a microfiche
reader printer showing my new design;

FIG. 2 is a right side elevational view thereof, the side
opposite being substantially the same;

FIG. 3 is a rear elevational view thereof; and

FIG. 4 is a top plan view thereof.

The bottom of the microfiche reader printer is plain
and unornamented.

FIG.1

FIG.2
